UNITED STATES PATENT OFFICE.

FRANK FREDERICK HENDRICKSON, OF GARFIELD, NEW JERSEY.

SUPPORTING MEMBER.

1,149,762.

Specification of Letters Patent.

Patented Aug. 10, 1915.

Application filed August 19, 1914. Serial No. 887,562.

To all whom it may concern:

Be it known that I, FRANK FREDERICK HENDRICKSON, a citizen of the United States, residing at Garfield, in the county of Bergen 5 and State of New Jersey, have invented certain new and useful Improvements in Supporting Members, of which the following is a specification, reference being had to the accompanying drawings.

10 This invention relates to certain improvements in supporting members and has relation more particularly to a device of this general character adapted to be employed in connection with musical instruments, and an 15 object of the invention is to provide a device of this general character having novel and improved means whereby the same may be applied in operative position with convenience and facility.

20 The invention also has for an object to provide a novel and improved device of this general character comprising a plurality of parts capable of convenient adjustment in order to fully meet the requirements of practice.

25 The invention consists in the details of construction and in the combination and arrangement of the several parts of my improved supporting member whereby certain 30 important advantages are attained and the device is rendered simpler, less expensive and otherwise more convenient and advantageous for use, all as will be hereinafter more fully set forth.

35 The novel features of the invention will be carefully defined in the appended claims. In order that my invention may be the better understood, I will now proceed to describe the same with reference to the accompanying drawings, wherein—

Figure 1 is a view in perspective of a supporting member constructed in accordance with an embodiment of my invention and in applied position; Fig. 2 is an enlarged fragmentary view, partly in section and partly in elevation, illustrating the lower portion of my improved supporting member and illustrating certain details thereof; Fig. 3 is a sectional view taken substantially on the line 3—3 of Fig. 1; Fig. 4 is an enlarged sectional view, partly in top plan and partly in section, illustrating the spanner member herein included together with its concomitant parts; and Fig. 5 is an 55 elevational view, detached, of a clamping member herein included.

As disclosed in the accompanying drawings, 1 denotes a substantially L-shape member; the stem of the member being adapted to overlie a hoop H of a bass drum D or other support, and provided with an opening 2 through which is adapted to be projected the threaded shank 3 of a clamping member 4 to coat with the stem of the member 1 in order to effectively maintain the same in applied position in a manner which is believed to be self-evident, and coacting with the threaded shank 3, as herein disclosed, is a wing nut 5, for the purpose of creating and maintaining the requisite 60 65 70 clamping action.

The free extremity of the stem of the member 1 is provided with the upstanding hollow boss 6 adapted to receive the lower extremity of a rod 7, said rod being maintained against displacement therefrom through the medium of the clamping screw 8 threaded through the boss 6 and adapted to engage the rod 7 in a manner which is believed to be self-evident.

9 denotes a block of predetermined configuration provided with the opening 10 in order that the same may be slidably engaged with the rod 7 and in order to maintain the block in a predetermined adjustment upon the rod 1 have threaded therethrough the clamping screw 11 operating in a manner which is believed to be self-evident. The block 9 is also provided with a second opening 12 disposed at right angles to the opening 10 and intersecting the same so that the action of the clamping screw 11 will cause the rod 7 to clampingly engage the rod 14 80 85 90 95 slidably disposed through the opening 12 so that said rod 14 may be effectively maintained in its different adjustments. One extremity of the rod 14 is formed to afford a notch 15 in order that a crash symbol C or the like may be conveniently suspended therefrom.

16 denotes a second block provided with an opening 17 whereby the same may be slidably engaged upon the rod 7 and further provided with a clamping screw 18 whereby said block 16 may be maintained 100 105 in its different adjustments, and this block 16 is provided with a second opening 19 disposed perpendicularly to the opening 17 and in communication therewith so that the rod 7 under the influence of the screw 18 110 may clampingly engage the shank 20 adapted to be disposed through the opening 19,

the outer extremity of said shank being provided with a spanner member 21, herein disclosed as substantially U-shape in form, adapted to engage the shell S of a tom-tom
5 T or the like, the supporting ring R of the tom-tom being adapted to be disposed around the hook member 22 longitudinally adjustable upon the shank 20, such adjustment being herein disclosed as afforded by
10 having the periphery of the shank 20, adjacent the spanner member 21, threaded, as indicated at 23, and disposed through the threaded opening 24 produced in the shank 20. The depending foot of the member 1
15 has projecting forwardly from the free extremity thereof, the arm or bracket 25 provided adjacent its free periphery with the depending screw member 26 with which contacts the wing nut 27 in order to adjustably
20 clamp in operative position the member 28, herein disclosed as formed from a single strand of wire of requisite gage bent upon itself intermediate its length to form a loop extremity 29 adapted to be disposed around
25 the screw 26, while the free extremities 30 of the member are angularly disposed and adapted to be projected within suitable openings or recesses 31 produced in the bottom of the wood drum W adjacent an extremity thereof, said drum W, when in applied position, also overlying the arm or bracket 25.

From the foregoing description, it is thought to be obvious that a supporting member constructed in accordance with my invention is of an extremely simple and comparatively inexpensive nature and is particularly well adapted for use by reason of the convenience and facility with which
35 it may be assembled, and it will also be obvious that my invention is susceptible of some change and modification without material departure from the principles and spirit thereof and for this reason I do not
40

wish to be understood as limiting myself to the precise arrangement and formation of the several parts herein shown in carrying out my invention in practice.

I claim:

1. A device of the character described comprising a member provided with engaging means and with a tubular boss, a rod adapted to be projected within said boss, means carried by the boss for holding the rod against displacement, a block adjustably mounted upon the rod, a spanner member carried by the block, and a hook member carried by the spanner member.

2. A device of the character described comprising a member provided with engaging means and with a tubular boss, a rod adapted to be projected within said boss, means carried by the boss for holding the rod against displacement, a block adjustably mounted upon the rod, a spanner member adjustably carried by the block, means common to the rod and spanner member for maintaining the same in their adjusted positions, and a hook member carried by the spanner member.

3. A device of the character described comprising a member provided with engaging means and with a tubular boss, a rod adapted to be projected within said boss, means carried by the boss for holding the rod against displacement, a block adjustably mounted upon the rod, a spanner member adjustably carried by the block, means common to the rod and spanner member for maintaining the same in their adjusted positions, and a hook member adjustably carried by the spanner member.

In testimony whereof I hereunto affix my signature in the presence of two witnesses.

FRANK FREDERICK HENDRICKSON.

Witnesses:

ADAM BRAYS,
MILES C. WHITEHEAD.
